UNITED STATES PATENT OFFICE.

HENRY M. BALL, SR., OF DAVIESS COUNTY, KENTUCKY.

PRINTING-MACHINE FOR CODE COMMUNICATION.

1,204,929.

Specification of Letters Patent. Patented Nov. 14, 1916.

Application filed October 22, 1915. Serial No. 57,339.

To all whom it may concern:

Be it known that I, HENRY M. BALL, Sr., a citizen of the United States, and residing in the county of Daviess and State of Kentucky, have invented a new and Improved 5 Printing-Machine for Code Communication, of which the following is a full, clear, and exact description.

My invention relates to printing machines 10 of a kind especially adapted for printing characters used in cipher codes for the purpose of concealing the meaning of the message written, and also in many instances for abbreviating such messages.

More particularly stated my invention 15 comprehends a printing mechanism provided with a keyboard and with movable type-bars actuated thereby and provided with types. The types and keys are arranged 20 in groups and so distributed as to facilitate the printing of the code characters in groups, the various characters being so arranged that their position in the group and in some instances the position of one group 25 relative to other groups, may be used for determining the meaning of the characters printed.

My invention is closely associated with 30 and is used in connection with a book or chart in which various numbers are shown, each number being associated with a particular syllable, word, sentence, or the like, having a meaning apparently unrelated to the number. Again, the numbers may be 35 used in different senses so as to convey different meanings according to a predetermined understanding, as hereinafter explained.

Reference is made to the accompanying 40 drawings forming a part of this specification, and in which like reference characters indicate like parts.

Figure 1 is a top view, partly in plan and 45 partly in section, showing one form of my printing machine; Fig. 2 is a section on the line, 2—2 of Fig. 1, looking in the direction of the arrow; Fig. 3 is a fragmentary elevation showing another form of my invention having additional type-bars; Fig. 4 is 50 a plan view of the mechanism appearing in Fig. 3; Fig. 5 is a plan view of a chart or paper sheet printed with the mechanism; Fig. 6 is a fragmentary section mating Fig. 3, and showing the ends of some of the type-bars and the printing types carried thereby; 55 Fig. 7 is a fragmentary elevation some-

what similar to Fig. 3, but showing the type-bars as used in a slightly different form of my machine; and Fig. 8 is a plan view of a chart or paper sheet printed by 60 type-bars of the kind represented in Fig. 7.

Mounted upon a board 9, is a casing 10 having a raised portion 11. The casing is further provided with a partition 12 disposed horizontally, and with another partition 13 disposed vertically. A platen roller is shown at 15, and extending through it is a shaft 16. The shaft carries a pair of hand wheels 17, and is mounted in bearings 18, each having the form of a post, 70 as may be understood from Fig. 2. Mounted rigidly upon the shaft 16 are a pair of ratchet wheels 19. A guide 20, made of sheet metal, is disposed adjacent the platen roller 15, and bent partially around the 75 lower portion thereof. Tension springs 21 are curved partially over the top of the roller. A chart 22, or sheet of paper, is guided by the springs 21 and guide 20. A pair of shifter bars 23 are located upon opposite sides of the platen roller and are each movable in the general direction of its own length. These shifter bars extend practically the entire length of the machine, and each of them is provided with a pawl 24. 80 The two pawls engage the ratchet wheels 19, and are used for turning these ratchet wheels, together with the platen roller, step by step. The shifter bars 23 are provided with collars 25, and engaging these collars 90 are springs 26, which rest against the partition 13.

Pivottally connected with one end of each shifter bar 23, is an arm 27, which is mounted rigidly upon a shaft 28. Another arm 29 is mounted rigidly upon this shaft, and resting upon this arm 29, is a shifter key 30, having, in this instance, the form of a pin, which extends through a portion of the casing 10. A spring 31 encircles the body 100 of this pin and also engages a guide 32, through which the pin also extends. Whenever the shifter key 30 is depressed the shifter bars 23 each move to the left according to Figs. 1 and 2, so that the pawls 24 105 turn the ratchets 19 a predetermined distance.

A guide plate is shown at 14, and disposed at the ends of this guide plate are a pair of rollers 33. An ink ribbon 34 engages 110 these rollers and is partially wound upon two spools 35 and 36. Connected with these

spools are ratchet wheels 37, 38, and engaging these ratchet wheels are pawls 39, 40, which are pivotally mounted upon the shifter bars 23. Leaf springs 41, 42 carried by the shifter bars, engage bosses 43, 44 carried by the pawls 39, 40, so that by pressure of the springs 41, 42, the pawls 39, 40 tend to remain in engagement with the ratchet wheels 37 and 38.

10 In order to prevent more than one of the pawls from engaging its ratchet at the same time, I provide a slide rod 46, having a pair of bosses 47, 48 extending downwardly from it and engaging the pawls 39, 40, as indicated in Fig. 1. The slide rod is provided with a head 46^a and extends through bearings 45. The operator by pressing against the head 46^a, can cause the pawl 40 to be moved out of engagement with the ratchet 20 wheel 38, and by pulling upon the head 46^a, the operator can cause the pawl 39 to move out of engagement with the ratchet wheel 37.

A number of keys are shown at 49, 50, 51, 25 52, 53, 54 and are conveniently designated as a group. Another group consists of keys numbered 55, 56, 57, 58, 59, 60. Other groups are shown at 61, 62 and 63. Each key is connected with a type-bar 64, by a flat 30 spring 65 so bent that the type-bar is located at substantially a right angle with reference to the general direction of movement of the key. The various springs 65 engage and are guided by a number of guide rods 66, so that pressure upon one of the 35 keys causes the corresponding guide rod to be driven in the direction of its length.

The keys and type-bars are so arranged that the keys of a group, which are here 40 six in number, are adapted to make as many marks, upon the chart or sheet 22, as the 45 number of keys which may be depressed at a particular instant. For instance, if two, three, or four of the keys of a group be depressed simultaneously, a number of marks 50 equal to the number of keys thus depressed, will be made upon the chart or sheet 22, and will occupy different relative positions upon this chart, such positions being arranged in substantially the same order of succession as 55 the keys used in making the marks. In order that this may be rendered clear, reference is made to Fig. 3.

The various type-bars 64 connected with 55 and actuated by the keys 49, 50, 51, 52, 53, 54, are provided with type-ends 49^a, 50^a, 51^a, 52^a, 53^a, 54^a. These type-ends are provided with impression characters 49^b, 54^b, which are distinguishable from each other. In this 60 particular instance, the impression character 49^b is a stipple, and the impression character 54^b is a dash. The relative arrangement or aggroupment of the keys, type-bars, and impression characters carried by the type-bars, is such that the depression of any key 65 of the group causes a mark to be made upon

the sheet or chart 22, both the form of the mark and its position relative to the sheet or chart, and also relative to any other marks which may be made at the same time, being such that the mark thus printed has 70 a significance because of its position.

The keys 49, 50, 51, 52, 53, 54, together constituting a group, are associated in the code book and in the mind of the operator, with the numbers "1," "2," "4," "8," "16," 75 and "32." The next group of keys 55, 56, 57, 58, 59, 60 are similarly associated with numbers beginning with "64" and successively doubling in value as is the case of the numbers associated with the first group. 80

Suppose, now, that in the code the number "1" has a definite meaning, which by aid of the code is readily translated into its definition or equivalent. Manifestly, whenever the key 49 is depressed and the character representing the number "1" is printed, this character can have attached to it the significance of the numeral 1 given it in the code book. This is true of each other key and the number corresponding to it and associated with it in the code book. When, therefore, the printing is finished, the sheet or chart may be sent through the mail or otherwise shipped to a distance, or displayed, and it will have its intended hidden 95 meaning.

The position of any mark or character made by the apparatus will, of course, indicate a different number in the code book, and such different number will have a different meaning. A stipple printed by the key 49 will have a different numerical meaning than a stipple printed by the key 51, and the translated meaning will be correspondingly different. 100

I find it convenient to have the keys of each group so arranged that when the printing is done upon the chart or sheet, it is read downwardly and then upwardly following the order of the keys 49, 50, 51, 52, 110 53 and 54.

In some instances, it may be desirable that instead of each separate key having a distinct numerical meaning, the various groups of keys may each have a numerical meaning to be ascertained by adding or totaling the numbers represented by the various marks printed. For instance, it may be understood between the operator and his correspondent that the latter upon receiving the chart or sheet is not to interpret the printed characters according to their individual numerical values, but rather according to their totals. Suppose, for instance, that the person receiving the chart or sheet finds printed upon it, in its upper left-hand corner, a character made by the key 49 and ordinarily meaning the number "1", and below this character, another character made by the key 51 and ordinarily meaning the number "8". 115 120 125 130

The person receiving the chart simply adds together the numbers "1" and "8", and thereby forms the composite number. Referring to his code book or to his memory, as the case may be, he ascertains the predetermined meaning intended for the number "9" and such meaning is the message he receives. By this arrangement, the difficulty of deciphering the code message is greatly increased, if not rendered impossible.

In Fig. 5, I show a portion of a chart or sheet 22 printed with stipples such as 50^b, 51^b. Dashes, such as 52^b, 54^c. These stipples and dashes indicate, by their form, that is, whether stipples or dashes, to which row of the group they belong, there being, of course, two rows in each group. They also indicate, by their relative positions, the numerical values with which they are associated. The operator by use of his code book can therefore readily ascertain the meaning of the message conveyed by the characters as thus printed.

In the form of the machine shown in Fig. 6, I provide for the use of additional keys in each group for the purpose of qualifying the work of the other keys. That is to say, I add keys which differ from other keys in the fact that they are used to vary the results of other keys as hereinafter explained.

In this construction, I employ a number of keys, 69, 70, 71, 72, 73, 74, 75, 76, 77, 78, ten in all, arranged as a group. A guide plate 79 steadies and guides the keys, and each key is provided with a retractile spring 80. The type-bars are shown at 64, and extend through a partition 81 and also through a guide plate 82, as well as through another partition 83. Except as here described, the construction and action of the various parts is the same as that above described with reference to Figs. 1 and 2. The type-bars 64 are encircled by springs 67, which engage collars 68 fixed upon the type-bars.

The guide plate 82 is shown fragmentarily in Fig. 7, and supported by this guide plate are the various type-ends 69^a, 70^a, 71^a, 72^a, 73^a, 74^a, 75^a, 76^a, 77^a, 78^a; these various type-ends being associated respectively with the keys numbered 69 to 78 inclusive. The type-ends are provided with impression characters 69^b, 70^b, 71^b, 72^b, 73^b, 74^b, 75^b, 76^b, 77^b and 78^b. It will be noted that the two uppermost impression characters 69^b and 78^b are dashes, which are disposed obliquely to the general direction of the two rows of type-ends. This is also the case with the impression characters 73^b, 74^b at the opposite end of the series. The impression characters 70^b, 71^b, 72^b, 75^b, 76^b, 77^b are quite analogous to those above described with reference to Fig. 3. The impression characters 69^b, 78^b, 73^b, 74^b, however, are in this instance used to qualify the meanings of the other impression characters. Suppose, for instance,

that the impression character 70^b has, according to the code, an arbitrary meaning by which it is understood as the letter "F". If now it is used for this purpose and the impression character 69^b is used above it, the two characters thus used may have collectively not the meaning "F", but rather a meaning understood as the word "For". If instead of the impression character 69^b being used, we substitute the impression character 73^b, the meaning may be not the word "For", but the word "From".

Fig. 8 shows a portion of a chart or sheet 84, and printed upon this sheet are a number of intelligible characters 69^c, 70^c, 72^c, 74^c, 80 75^c, 76^c. Comparing Fig. 8 with Fig. 7, it will be noted that the intelligible characters thus printed, are made from certain of the type-ends shown in Fig. 7. Each intelligible character shown in Fig. 8 has its meaning according to the code, and the slanting characters 69^c, 74^c, adjacent the top and bottom of the chart or sheet, are here used to qualify meanings of the other characters as above described and as recorded in the code book.

I do not limit myself to the precise mechanism here shown as variations may be made therefrom without departing from the spirit of my invention.

Having thus described my invention, I claim as new and desire to secure by Letters Patent:

1. In a printing machine for code communication, a platen roller, ratchet wheels on the shaft of the roller, a pair of ribbon carrying rollers adjacent the platen roller, ratchet wheels on the shafts of the ribbon carrying rollers, a pair of sliding and spring pressed bars, pawls carried by the said bars and engaging the ratchet wheels of the platen roller, pivoted and spring pressed pawls on the said bars and engaging the ratchet wheels of the ribbon carrying rollers, a key, and means for operating the said bars from the key.

2. In a printing machine for code communication, a platen roller, ratchet wheels on the shaft of the said roller, a pair of ribbon carrying rollers adjacent the platen roller, ratchet wheels on the shafts of the said rollers, a pair of sliding and spring pressed bars, pawls carried by the bars for operating the ratchet wheels of the platen roller and the ribbon carrying rollers, a shaft having three arms with two of which the sliding bars are connected, and a sliding and spring pressed key engaging the third arm of the said shaft.

3. In a printing machine for code communication, a platen, a plurality of sliding and spring pressed type bars, a plurality of keys arranged approximately at right angles to the type bars, a flat and curved spring connecting said key with a type bar,

and guide rods below the springs and with which the springs engage when pressure is applied to the keys.

4. In a printing machine for code communication, a platen roller having ratchet teeth at its ends, a plurality of type bars, a plurality of keys for operating the type bars, ribbon carrying rollers having ratchet wheels thereon, a pair of sliding and spring 10 pressed bars carrying pawls engaging the ratchet wheels of the platen roller and the ratchet wheels of the ribbon rollers, and a key operatively connected with the said sliding bars.
- 15 5. In a printing machine for code communication, a platen roller having ratchet teeth, a plurality of type bars, a plurality of keys for operating the type bars, ribbon carrying rollers having teeth, a pair of sliding and spring pressed bars carrying pivoted pawls for engaging the ratchet wheels 20 of the platen roller and ribbon rollers, a key for operating the sliding bars, and means for alternately moving the pawls of the ratchet wheels of the ribbon rollers out 25 of engagement with the ratchet wheels.

6. In a printing machine for code communication, a platen roller, mounted on a horizontal axis and having ratchet wheels

at its ends, a plurality of type bars, keys 30 for operating the type bars, ribbon carrying rollers mounted upon vertical axes and having ratchet wheels at their ends, sliding and spring pressed bars, a key for operating the bars, pawls carried by the sliding 35 bars and engaging the ratchet wheels of the platen roller, pivoted and spring pressed pawls mounted on the upper faces of the sliding rods for engaging the ratchet wheels of the ribbon rollers, and a transverse sliding rod having projection engaging the last 40 named pawls.

7. In a printing machine for code communication, a platen roller, a plurality of type bars, keys for operating the type bars, 45 ribbon rollers, sliding and spring pressed bars, a key for operating the sliding bars, means for operating the platen roller from the sliding bars, means for operating the ribbon rollers from the sliding bars, and 50 means whereby the operating means of the ribbon carrying rollers are alternately rendered inoperative.
